UNITED STATES PATENT OFFICE.

WILLIAM AUSTIN JOHNSON, OF FAIRMONT, WEST VIRGINIA.

CLOTHESLINE-CLAMP.

1,368,805.

Specification of Letters Patent. Patented Feb. 15, 1921.

Application filed March 2, 1920. Serial No. 362,829.

To all whom it may concern:

Be it known that I, WILLIAM AUSTIN JOHNSON, a citizen of the United States, and a resident of Fairmont, in the county of 5 Marion and State of West Virginia, have invented certain new and useful Improvements in Clothesline-Clamps, of which the following is a specification.

My invention relates to clamps for securing 10 supporting the clothes lines on a pole or prop, and the purpose of my invention is the provision of a simple, inexpensive and efficient clamp which will effect a locking of the clothes line to the prop so that accidental 15 displacement of the line is positively prevented.

I will describe one form of clamp embodying my invention and will then point out the novel features thereof in claim.

20 In the accompanying drawing:

Figure 1 is a view showing in side elevation one form of clamp embodying my invention in applied position upon a prop.

Fig. 2 is a front elevation of the clamp 25 shown in Fig. 1.

Similar reference characters refer to similar parts in each of the views.

Referring specifically to the drawings, the clamp consists of a single length of resilient 30 wire having a substantially circular intermediate portion 15 bent upon itself at one end to provide an eye 16. The opposite end of the circular portion 15 is bent inwardly then looped and bent outwardly and 35 downwardly to provide a hook 17, the wire being extended from the hook downwardly as at 18, twisted about the circular portion as at 19, and then extended radially from such circular portion to provide a shank 20. 40 The shank 20 is threaded at its lower end as at 21 for engagement with the end of the prop 22 whereby the shank supports the clamp as a unit in position upon the prop.

In the releasing position of the clamp as 45 shown in dash lines in Fig. 1, the eye 16 occupies a spaced position with relation to the

hook 17 under the resilient action of the wire of which the circular portion 15 is formed, and through this space the clothes line is inserted into the circular portion of the clamp. 50 After the clothes line has been inserted in this manner, the eye 16 is forced downwardly and over the hook 17 and retained in this position under the tendency of the wire to return the eye to its normal position. 55 As shown in Fig. 1, the hook 17 is slightly inclined downwardly so as to prevent accidental displacement of the eye from the hook. In this manner the clothes line is locked within the clamp and the only way 60 in which the line can be removed from the clamp is by manually removing the eye 16 from the hook 17.

In devices of this character heretofore proposed they merely provide some form of 65 clasp for temporarily retaining the line upon the prop so that when sufficient pull is exerted upon the prop or clothes line, a separation of the two is effected. In my invention the clamp positively locks the clothes 70 line to the prop and such accidental separation of the two is positively prevented.

Although I have herein shown and described only one form of clothes line clamp embodying my invention, it is to be understood that various changes and modifications may be made herein without departing from the spirit of the invention or the spirit and scope of the appended claim. 75

What I claim is:—

80 A clothes line clamp for props comprising, a single length of resilient wire having a substantially circular intermediate portion, one end of said portion being bent to provide an eye, the opposite end of said portion being bent inwardly and then outwardly to provide a hook, the hook end of the wire being bent back upon itself and extended and twisted about the circular portion and then extended radially therefrom to provide 85 a shank. 90

WILLIAM AUSTIN JOHNSON.
